UNITED STATES PATENT OFFICE

THOMAS A. E. DICKINSON, OF POLAND, OHIO

SAFETY CONTROL DEVICE FOR FURNACES

Application filed March 26, 1929. Serial No. 350,110.

This invention relates to safety control devices for furnaces or stoves, and more particularly comprises an automatic damper carried on the usual smoke pipe leading from the furnace or stove to the chimney and operative upon overheating of the smoke pipe to automatically open, thereby checking the draft through the furnace and permitting the smoke pipe to cool down to a point where danger of fire due to the overheating of the smoke pipe or furnace is entirely eliminated. In carrying out this invention a fusible element is employed and preferably maintained in intimate engagement with the smoke pipe so that the heat of the smoke pipe is rapidly conducted to the element, and suitable connections are provided between the fusible element and damper so that upon fusion of the fusible element due to overheating of the pipe, the damper automatically opens, permitting air to flow into the smoke pipe through the damper to thereby check the draft through the furnace.

It is well known that innumerable fires and property damage result from overheated smoke pipes, furnace flues and furnaces and the principal object, therefore, of the present invention is to provide positive means to insure against such occurrences and to automatically and quickly check and reduce the heat of smoke pipes, furnace flues and furnaces so that over-heating thereof is entirely eliminated.

Another object of the present invention is to provide a device which can readily and quickly be applied to smoke pipes such as are used in connection with substantially all commercial types of furnaces in use today without radical modification or alteration of the existing smoke pipe structures so that the installation can be quickly effected at a minimum expense.

Another object of the present invention is to provide a device of this class which is accurate and effective in operation and is of such a simple character that it may be readily installed without the necessity of employing skilled mechanics.

A further object is to provide a device which, when once assembled, will not get out

of order, and after the fusible element has been broken, may be quickly restored to operative condition by placing a new fuse in position without the necessity of disconnecting any of its operating parts.

Further objects and advantages will be readily apparent as the description of the invention proceeds and while several forms of the invention are illustrated in the accompanying drawings as indicating various forms, it is to be distinctly understood that the invention is not to be limited to the precise embodiments as shown, but that suitable alterations and changes in the details of construction may be resorted to so long as they do not depart from the scope or spirit of the invention as defined in the appended claims.

In describing the invention, reference will be had to the accompanying drawings forming part hereof and in which:

Fig. 1 is a fragmentary front view of my invention applied to a vertically extending smoke pipe.

Fig. 2 is a fragmentary vertical central sectional view taken along the line A—A of Fig. 1.

Fig. 3 is a horizontal sectional central view taken along the line B—B of Fig. 2.

Fig. 4 is a fragmentary side elevation of the lower portion of my invention.

Fig. 5 is a detail sectional view of a portion of my device as illustrated in Fig. 3.

Fig. 6 is a fragmentary front view of a modified form of my invention showing the same applied to a horizontally extending smoke pipe.

Fig. 7 is a vertical central sectional view taken along the line C—C of Fig. 6.

Fig. 8 is a fragmentary side elevation of my invention as illustrated in Fig. 6.

Fig. 9 is a fragmentary front view of the device illustrated in Fig. 6 with the sliding damper removed so as to clearly indicate the structure of the collar surrounding the smoke pipe as well as the openings in the smoke pipe itself.

Fig. 10 is a sectional view of a further modification of my invention.

Fig. 11 is a front view of the device as illustrated in Fig. 10.

Fig. 12 is a rear view of the same modified form.

Fig. 13 is a fragmentary sectional detail view indicating the manner of securing the fusible element to the smoke pipe.

Fig. 14 is a detail sectional view illustrating the manner of mounting the pulley as shown in Figs. 3 and 4.

Referring more particularly to the drawings, in which the reference characters indicate similar parts throughout the views, I have indicated a smoke pipe 1 which receives exhaust gases from the furnace at one end and passes the same to a chimney through the other end, and which is provided with one or more openings 2 and 3 cut through the wall thereof; the openings illustrated being shown as of rectangular formation. Surrounding the smoke pipe 1 is a collar 4 which may be formed of sheet metal or other suitable material and comprises substantially a split sleeve provided at the meeting edges thereof with upstanding flanges 6 and 7 having bolt holes therein adapted to receive bolts 9 by means of which the meeting edges of the collar 4 are drawn together so as to securely clamp the same around the smoke pipe 1. The bolts 9 receive nuts 10 on the ends thereof so that by manipulation of the nuts, the collar can be removed and replaced with great facility.

In describing the smoke pipe 1, I have indicated that the same is provided with a plurality of openings, but it is to be understood, of course, that I may, if desirable, form merely a single opening and that the configuration of the opening thus formed is immaterial so long as it is of sufficient area to permit air to flow into the smoke pipe and thereby check the draft through the furnace.

The collar 4 which has been secured to the smoke pipe 1 is likewise provided with a series of openings 11 and 12 which conform to the configuration of the openings 2 and 3 in the smoke pipe and which are adapted to align with the openings 2 and 3 when the collar 4 has been clamped in position so that the openings in the smoke pipe 1 and the openings in the collar 4 register with each other.

The collar 4 is provided at its marginal edges immediately above and below the openings 11 and 12 with integrally formed flanges 13 and 14 terminating in vertically extending ears 15 and 16 spaced from the wall of the collar 4 to provide grooves 17 and 18 which act as guides for the sliding damper 19 and while these guides are indicated as being formed integral with the collar so as to permit a close fit between the sliding damper 19 and the wall of the collar 4, it is to be understood that any suitable means for guiding this damper may be employed without affecting the principle or mode of operation.

From the foregoing it will be seen that a very simple, compact and efficient manner of securing the sliding damper to the smoke pipe of a furnace is provided and that its simplicity makes it possible to assemble the same on smoke pipes as commercially used today without the employment of any skilled mechanics.

In the collar 4 to one side of the openings 11 and 12, I provide an additional opening 20 which is clearly indicated in Figs. 1 and 3 and which extends circumferentially of the collar 4, thereby exposing that portion of the smoke pipe 1 lying within the limits of the opening 20.

The sliding damper 19 has secured thereto a fuse holder 21 comprising a rivet provided with an enlarged conical head 22 tapering outwardly from the sliding damper and the collar 4 is provided with a similar fuse holder 23 adjacent the edge of the elongated opening 20.

The fusible element is indicated at 24 and comprises a band or the like structure having at its opposite ends openings 25 which are of larger diameter than the conical heads of the fuse holders so that the fusible element may be readily connected to and disconnected from the fuse holders and the replacement of the fusible element thus easily accomplished.

By providing the fuse holders 21 and 23 with the conical outwardly flaring heads 22, it will be understood that when in position there is no possibility of the fuse elements becoming detached from the holders since the tension on the fusible element tends to force the same toward the collar 4, thereby insuring proper positioning of the fusible element at all times, and also causes at least a portion of the latter to contact with the smoke pipe as will be apparent from an inspection of Fig. 3 from which it will be seen that when the fusible element 24 has been secured to the fuse holders 21 and 23, it will lie in contact with the smoke pipe 1 so that the heat therefrom will be readily conducted to the element.

The fusible element 24 assumes the position shown in Fig. 3, that is, in contact with the smoke pipe 1, because of the tension placed on the fusible element by means of a weight exerting a pull on the front end of the sliding damper 19 so that when the device has been fully assembled the fusible element 24 is maintained in intimate contact with the heated smoke pipe 1.

The sliding damper 19 comprises in reality a door structure of the same curvature as the smoke pipe 1 and collar 4 and has at its front edge an upstanding flange 26 through which is passed an eyelet or other suitable fastening means 27 to which is secured one end of a chain or other flexible element 28 as clearly indicated in Figs. 1, 3 and 4.

The chain 28 is trained over a pulley 29 which is suitably supported on the collar 4 by means of a rivet 30 and the pulley 29 is provided with a vertical flange 31 to prevent displacement of the chain or flexible element therefrom.

To the other end of the flexible element 28 I secure a suitable weight 32, it being noted from Fig. 4 that the flexible element 28 assumes a vertical position after having passed over the pulley 29 so that upon breaking of the fusible element 24 the weight 32 exerts a downward pull on the flexible element 28 which is translated to a horizontal movement thereby sliding the damper 19 to open position and permitting air to flow into the smoke pipe and thence to the chimney, thereby effectively checking the draft through the furnace.

I have described the sliding damper 19 as being provided with a flange 26 having the eyelet 27 therein and have also particularly described one manner of mounting the pulley 29, but it is believed that it will be readily understood that these constructions may be changed to suit varying conditions as the varying uses may demand.

Referring now to Figs. 6 to 9 inclusive, I have therein illustrated a modified form of the invention adapted for application to a horizontally extending smoke pipe 1 as distinguished from the vertical smoke pipe shown in Fig. 1. In other respects the form of the invention disclosed in the said figures is similar to that disclosed in Figs. 1 to 4.

In view of the fact that the form of the invention as shown in Figs. 6 to 9 is applied to a horizontally extending smoke pipe 1, it is unnecessary to employ the pulley 29 and the flexible element 28 is, therefore, secured to the flange 26 of the sliding damper 19 so that the flexible element is suspended in vertical position and has secured to the end thereof of the weight 32 so that upon fusion of the element 24 the weight 32 exerts a direct pull on the damper 19 so as to open the same and permit air to flow into the smoke pipe 1 and thence to the chimney to thereby check the draft in the furnace; a normally slack chain 28' may be disposed between one of the bolts 9 and the weight 32 to support the latter and prevent it from falling to the floor when after the fusing of the fusible element, the flexible element 28 is no longer effective for this purpose.

From the description thus far given of the device, it will be clearly apparent that the weight 32 exerts a constant tension on the fusible element 24 through the sliding damper 19 and that it is due to this tension that the fusible element 24 contacts intimately with the smoke pipe 1.

In Figs. 10 to 13, I have indicated another modification of the present invention. In this instance, while I employ the same principle of operation, I have illustrated the inven-

tion as being applied to the ordinary check damper of a furnace construction such as to be found on many furnaces now on the market.

In this form of the invention the check damper is indicated at 33 and is provided with the usual operating element 34 by means of which the damper 33 can be controlled under ordinary operating conditions.

Suitably secured to the damper 33 by means of rivets or similar fastenings 35 is an outwardly extending arm 36 to which is secured one end of a flexible element 37 here indicated as a chain and the opposite end of the flexible element 37 is secured to a link 38 having at one end a hook 39 engageable in an aperture 40 in one end of the fusible element 41.

The opposite end of the link 38 is provided with an eyelet 42 by means of which the weight 43 is secured thereto.

The fusible element 41 is secured to the smoke pipe by means of a fuse holder 44 which is provided with the conical head similar in construction to the conical head 22 of Fig. 5, but in this case, the fuse holder is secured to the smoke pipe by means of a nut 45 threaded on the shank 46 of the fuse holder.

It is believed to be obvious that the form of the invention now being described, operates in substantially the same manner as the devices shown in Figs. 1 and 6, that is, that tension exerted on the fusible element 41 by the weight 43 causes the fusible element to lie in intimate contact with the smoke pipe so that heat is conducted thereto rapidly and that in the event of the smoke pipe becoming heated above a predetermined temperature, the fusible element will break, thereby releasing the weight, and opening the check damper to permit air to flow into the smoke pipe.

By reference to Fig. 10, it will be seen that the flexible element 37 is normally maintained slack so as not to interfere with the ordinary operations of the check damper but that upon release of the weight, the slack is taken up and the check damper opened.

In all of the forms of the present invention, I have described the fusible element as comprising a band of material, but I desire it to be understood that any form of fusible element may be used that will fulfill the requirements as described herein and it is to be understood that the fusible element employed is of a soft pliable material so that the tension exerted by the weights will cause the fusible element to conform to the configuration of the smoke pipe to which it is applied.

I have also described the present invention as employing weights for the purpose of opening the dampers, but it is my intention to include equivalent structures that will per-

form the same function without changing the principle of operation.

In all of the illustrated forms of the present invention it will be seen that I have provided a very simple manner for securing the fuse in position. In the forms indicated in Figs. 1 and 6, it is merely necessary to restore the device to normal condition to replace the fusible element 24 by passing the head of the fuse holders 21 and 23 through the enlarged openings in the ends of the fusible element and that the weight 32 automatically holds the fusible element against displacement. In the form shown in Fig. 10, the fusible element 15 is readily attached by passing the head 44 through the opening in the end of the fusible element and hooking the link 38 with its weight 43 through the opening in the opposite end of the fusible element and that due to the tension caused by the weights the fusible elements are held in such position as to prevent any possible dislodgment.

From the foregoing, it will be seen that my invention provides an exceedingly simple, compact and inexpensive construction which may be applied without materially changing known furnace constructions and that due to its simplicity and relatively few parts, it will be accurate and reliable in operation at all times.

Having thus described my invention, I claim and desire to protect by Letters Patent of the United States:

1. A device of the character described comprising a furnace smoke pipe having an opening in one of its walls, a fusible element supported by the smoke pipe and in contact therewith, a damper carried by said smoke pipe and normally closed to cover the said opening, and means operable upon breaking of the fusible element to open said damper.

2. A device of the character described comprising a furnace smoke pipe having an opening in one of its walls, a fusible element supported by the smoke pipe, a damper carried by said smoke pipe and normally closed to cover the said opening, a weight supported by said fusible element, and means connecting the weight and damper operable to open said damper upon fusion of the fusible element.

3. A device of the character described comprising a furnace smoke pipe having an opening in one of its walls, a fusible element supported by the smoke pipe and in contact therewith a damper carried by said smoke pipe and normally closed to cover the said opening, a weight supported by said fusible element and a flexible member secured to said weight and cooperating with said damper to open the damper upon fusion of the fusible element.

4. A device of the character described comprising a smoke pipe having an opening in the wall thereof, a damper closing said open-

ing, a fusible element carried by the smoke pipe in contact therewith, means connecting the fusible element and damper, and a weight associated with said fusible element and operable to open the damper upon fusion of the fusible element.

5. A device of the character described comprising a smoke pipe having an opening in the wall thereof, a sliding damper controlling said opening, a fusible member secured to the smoke pipe and damper and contacting with said smoke pipe, and a weight attached to said damper and operable upon fracture of the fusible element to operate said damper.

6. A device of the class described comprising a furnace smoke pipe having an opening in the wall thereof, a collar having an opening therein registering with the opening in the smoke pipe and secured to said smoke pipe, guideways on said collar, a damper slidable in said guideways for controlling the openings, a fusible element normally holding the damper in closed position, and means operable upon fracture of the fusible element to open said damper.

7. A device of the character described comprising a furnace smoke pipe having an opening in the wall thereof, a collar secured to said smoke pipe and having an opening registering with the opening in the smoke pipe, a damper slidable about the collar and normally disposed in a position to cover said openings and thermally controlled means operable when the smoke pipe attains a predetermined temperature to slide the damper to another position to thereby uncover said openings.

8. A device of the character described comprising a furnace smoke pipe having an opening in the wall thereof, a sliding damper normally closing said opening, and means including a weight and a fusible element supporting the weight and operable upon overheating of the smoke pipe to release the weight and slide the damper to open position.

9. A device of the character described comprising a furnace smoke pipe having an opening in the wall thereof, a collar encircling said smoke pipe and having an opening therein registering with the opening in the smoke pipe, guides on said collar, a damper slid able in said guides to control the said openings, a fusible element secured to said collar and damper normally holding the damper in closed position, a flexible element secured to said damper, and a weight on said flexible element operable upon fracture of the fusible element to slide the damper to open position.

10. A device of the character described comprising a furnace smoke pipe having an opening therein, a collar surrounding said pipe and having openings therein, one of which is adapted to register with the opening in the smoke pipe, a sliding damper on said

collar, normally closing the registering openings, a fusible element secured to said collar and damper and lying in the other opening in the collar so as to contact with the smoke pipe, and means operable upon fracture of the fusible element to slide the damper to open position.

11. A device of the character described comprising a furnace smoke pipe having an opening therein, a collar surrounding said pipe and having openings therein one of which is adapted to register with the opening in the smoke pipe, a sliding damper on said collar normally closing the registering openings, fuse holders on said sliding damper and collar comprising studs having inwardly tapering heads, a fusible element provided with openings of greater diameter than the said heads secured to said fuse holders at opposite ends and lying in the other opening in the collar so as to contact with the smoke pipe, and means operable upon fracture of the fusible element to slide the damper to open position.

25 12. A device of the character described comprising a furnace smoke pipe having an opening therein, a damper normally closing said opening, a fusible element supported by said smoke pipe and having connection with said damper, and means cooperating with said fusible element for placing the same under tension and maintaining it in intimate contact with the smoke pipe, said means including a weight connected to said damper and operable to open the same upon fracture of the fusible element.

In witness whereof I have hereunto set my hand this 23rd day of March, 1929.
